UNITED STATES PATENT OFFICE.

WALTER P. SCHEURMANN, OF DAYTON, OHIO.

CENTRIFUGAL PUMP, BLOWER, AND THE LIKE.

1,050,698.

Specification of Letters Patent. Patented Jan. 14, 1913.

Application filed May 17, 1912. Serial No. 697,856.

To all whom it may concern:

Be it known that I, WALTER P. SCHEURMANN, a citizen of Switzerland, and resident of Dayton, in the county of Montgomery and State of Ohio, have invented certain new and useful Improvements in Centrifugal Pumps, Blowers, and the Like, of which the following is a full, clear, and exact description.

10 The object of the present invention is to provide a centrifugal pump in which a high efficiency shall be secured with a cheap and simple construction by eliminating the necessity of accurately shaped stationary passages, and instead converting any desired amount of velocity head into pressure in suitable passages rotating with the pump impeller. The water leaves the impeller of a centrifugal pump at high velocity, and 15 any sudden change in direction or velocity of flow means a reduction in efficiency, which, however, is serious only at the higher velocities, as the loss in energy contained in the water is proportional to the square of 20 the velocity and at sufficiently reduced speeds the highest possible loss is so small as to be negligible.

In accompanying drawings Figure 1 shows a sectional elevation of a centrifugal pump, Fig. 2 a transverse sectional elevation of a centrifugal pump with a double inlet, Fig. 3 a transverse sectional elevation of a centrifugal pump with a single inlet and Fig. 4 a diagrammatic view of the 35 impeller. Fig. 5 shows an impeller arranged to revolve in a body of water without the usual casing and Fig. 6 shows two impellers mounted to rotate upon a vertical shaft located in a vertical pipe.

40 Similar numerals refer to similar parts throughout the several views.

Referring now principally to Figs. 1 and 3, 10 represents an annular succession of spirally disposed curved vanes, which are 45 located between and secured to two circular plates, 11 and 12. Plate 11 is rigidly secured to a rotatable shaft 13, rotating in bearings 18 and 19, while plate 12 has a central inlet aperture 14. The inner ends of 50 the vanes approximately coincide with the edges of the aperture 14, while the outer

ends are a substantial distance from the edges of the plates.

As seen in Fig. 3 the space between the plates is substantially uniform to the outer 55 ends of the vanes, from which point the plates flare outward gradually but considerably increasing the capacity of the space 15 between the plates.

The impeller rotates in a casing 16, whose 60 form is of little or no consequence. As shown in Figs. 1, 2 and 3 of the drawings, the space within the casing not occupied by the impeller is sufficient to accommodate the water discharged from the impeller, but 65 for reasons which will presently be explained, the casing may be formed in a simple and inexpensive manner and not requiring careful or expensive work in fitting the parts together. An inlet 17 conducts 70 water to the aperture 14 in the impeller while outlet 21 carries the water from the casing.

As the absolute velocity (A, Fig. 4) with which the water leaves the impeller is approximately equal to and in the same direction as the circumferential velocity (C, Fig. 4) of the impeller at the point of discharge, it has been recognized before that it would be of advantage to have the discharge 75 passages rotate in the same direction as the impeller, in order to reduce the relative velocity between the water flow in the guide passages and the sides of the pump, and so reduce the friction of the water. In Fig. 4 80 the dotted curve line shows the relative path of water and wheel. The absolute discharge velocity (A) is highest as the water gets past the impeller vanes and is gradually reduced in the passage 15 and leaves at the 85 small velocity F. The form of the plates 11 and 12 should be such that the increasing capacity of the space 15 would make the velocity at F so low that the effects of whatever impediments the water may encounter 90 thereafter are negligible.

In Fig. 2 the vanes 10 are secured to a hub 20 which is secured to the shaft 13. In this style each one of the plates 11 and 12 has an inlet aperture 14, while the casing 16 is 100 supplied by two inlets 17. The construction of the impeller shown in Fig. 5 is substan-

tially the same as that shown in Fig. 3. In this figure, however, the impeller is mounted upon a vertical shaft and water is supplied to the inlet aperture 14 by an inlet pipe 25, 5 which is attached to the bottom of the tank in which the impeller rotates.

The arrangement shown in Fig. 6 is adapted to such uses as deep well pumping, et cetera. For this purpose the impeller is 10 composed of saucer shaped plates 30 and 31 placed one within the other with the vanes 32 secured to each, maintaining the distance between them.

As in the constructions shown in Figs. 2, 15 3 and 5, the plates 30 and 31 extend beyond the outer ends of the vanes, although the plate 30 extends much shorter distance than plate 31. The object of the saucer shaped plates is to direct the water in a direction more 20 nearly parallel with than tangential to the axis. The relative shape of the plates is preferably such that one end of a radial line midway between them would be approximately perpendicular to the axis while 25 the other end of the line would be approximately parallel with the axis of the impeller.

Two or more impellers of the form shown in Fig. 6 may be rotated upon a single shaft 30 in a suitable casing.

I am aware that minor changes may be made in the form or construction of the parts shown while remaining within the scope of my claims.

35 What I claim is as follows:

1. An impeller for a centrifugal pump comprising an annular succession of radiating vanes secured to and separating a pair of circular plates, one of said plates being 40 rigidly secured to a rotatable shaft, the other having a central inlet aperture whose periphery approximately coincides with the inner ends of the vanes, the outer parts of the plates extending beyond the vanes and 45 being formed so the distance between them increases from the vanes to their edges.

2. An impeller for a centrifugal pump comprising an annular succession of radiating vanes secured to and separating a pair 50 of circular plates, means for securing the impeller to a rotatable shaft, one of the plates having a central inlet aperture whose periphery approximately coincides with the inner ends of the vanes, the outer parts of 55 the plates extending beyond the vanes and being formed so the distance between them increases from the vanes to their edges.

3. An impeller for a centrifugal pump comprising an annular succession of spirally disposed curved vanes of uniform cross-section, secured to and separating a pair 60 of circular plates, means for securing the impeller to a rotatable shaft, one of the plates having a central inlet aperture

whose periphery approximately coincides 65 with the inner ends of the vanes, the outer parts of the plates extending beyond the vanes and being formed so the distance between them increases from the vanes to their edges. 70

4. An impeller for a centrifugal pump comprising an annular succession of spirally disposed curved vanes secured to and separating a pair of circular plates, means for securing the impeller to a rotatable shaft, 75 one of the plates having a central inlet aperture, the outer parts of the plates extending beyond the vanes and being formed so the distance between them increases from the vanes to their edges, the relative form of 80 the plates being such that the direction of a radial line midway between them will gradually change from approximately perpendicular to approximately parallel with the axis of the impeller. 85

5. In a centrifugal pump, in combination, an impeller comprising a rotatable member adapted to rotate in and impart rotary motion to a body of fluid, whereby said fluid is made to flow from a point at or near the 90 axis of the impeller to a point farther removed therefrom, means for conducting fluid to the impeller, and means embodied in the construction of the impeller whereby fluid which has flowed a given distance from the axis receives no rotary motion from the impeller other than that imparted by friction, and for finally directing the fluid moved by the impeller in a direction more 95 nearly parallel with than tangential to its 100 axis.

6. An impeller for a centrifugal pump comprising an annular succession of radiating vanes secured to and separating a pair of circular plates, means for securing the impeller to a rotatable shaft, one of the plates having a central inlet aperture, the plates extending beyond the ends of the vanes, thereby furnishing a rotating guide for the fluid, and being so formed that the 105 volume of fluid may expand in a direction parallel with the axis of the impeller as it flows from the ends of the vanes to the edges 110 of the plates.

7. An impeller for a centrifugal pump, 115 comprising an annular succession of radiating vanes secured to and separating a pair of saucer shaped plates placed one within the other, means for mounting the impeller on a rotatable shaft, and an inlet to the 120 space between the plates, the outer edges of the plates extending beyond the ends of the vanes and being so shaped with reference to each other that the distance between them increases from the ends of the vanes to the 125 edges of the plates.

8. An impeller for a centrifugal pump, comprising an annular succession of radiat-

ing vanes secured to and separating a pair of saucer shaped plates placed one within the other, the inner one being rigidly secured to a rotatable shaft, the other having 5 a central inlet aperture, the outer edges of the plates extending beyond the ends of the vanes.

In testimony whereof I have affixed my signature in the presence of two subscribing witnesses.

WALTER P. SCHEURMANN.
